JOINT FOR SHEET PILES

August Schaack, Esch/Alzette, Luxembourg, assignor to Acieries Reunies de Burbach-Eich-Dudelange Societe Anonyme, Luxembourg, Grand Duchy of Luxembourg, a company of Luxembourg

Application July 30, 1947, Serial No. 764,748
In Luxembourg December 28, 1943

Section 1, Public Law 690, August 8, 1946
Patent expires December 28, 1963

1 Claim. (Cl. 61—62)

1

This invention relates to joints for sheet piles, and more particularly to joints of the type in which connection between successive or adjacent sheet piles is effected by the inter-engagement of joint portions of bifurcated cross-section, the furcations of each joint portion comprising a free end or edge hook and an inwardly spaced claw, the space between the hook and claw affording a channel to receive as a snug fit a correspondingly shaped hook on the adjacent sheet pile, the claw and hook on the latter pile receiving between them the hook of the other pile. This form of joint is referred to as a double hook joint.

As the result of compression and tensile strains the known forms of these double hook joints have a tendency to spread or open out so that the joints loosen. The object of the present invention is to remedy this weakness or to increase the strength of the joints without introducing added bulkiness or protrusion of the joints laterally beyond that which at present obtains.

According to this invention a double hook joint for sheet piles is characterised in that the peak or ridge of the free edge of each hook portion is so related to its inner or root part that when a joint is effected, the shortest distance across the peaks or ridges of the two hook portions is contained in a plane parallel with the planes of the sheet piles.

The invention will now be more clearly understood by reference to the accompanying drawings in which:

Figure 1 shows a known cross-section of joint for sheet piles; and

Figure 2 is a cross-section through a joint forming an embodiment of the present invention.

Referring to the drawings, the webs *c* and *d* of the two sheet piles have in common triangular cross-section hooks *e* at the ends of tenons *h* formed co-extensive with the webs, the peaks or ridges of the hooks *e* forming the appropriate free ends or edges of the sheet piles. Spaced inwardly from each hook *e* is a claw *g* inclined so as to be closely along the inclined side *e*¹ of the appropriate hook *e*, this side *e*¹ being that which is most remote from the claw *g* of the sheet carrying such hook. Thus each hook *e* slides in a corresponding channel constituted by the sides *g*², *h*² and *e*², the sides *h*² being at right angles to the base sides *e*² parallel with the sides *e*³ of the hooks *e*, so that the apices *e*⁴ of the hooks *e* of each joint are staggered. That is, they form the termini of a diagonal S—O—S¹, in which O is at the centre of the bases *e*², the sides *h*², *e*² and *e*³

2

appropriate to each hook forming a right angle Z in the form shown in Figure 1.

Also, the base portion *e*² of each hook is normal or perpendicular with respect to the plane of the sheet pile, so that during tractive effort the flat base portions *e*² of the hooks abut against each other in a plane transverse to the mean direction of tensile strain.

It will be noted that the whole of the joint 10 constituted by the inter-engaging hooks is uni-lateral relative to the co-planar faces *c*' and *d*' of the sheet piles, so that on one side of the assembly of piles there are no lateral projections, and in the present invention care is taken to keep 15 to this feature.

However, in maintaining the said uni-lateral disposition of each complete joint in the known arrangement shown in Figure 1, the staggering or stepping of the peaks *e*⁴ tends to cause the 20 compression load on the sheet piles at the joint to be applied along the diagonal S—O—S¹ and to unduly strain and often bend outwards the claws *g* away from their sheet piles, by reason of the sides *e*³ tending merely to slide along the sides 25 *h*² in the direction parallel with the plane of the webs *c* and *d* and thereby transferring the whole of the load across the sides *e*¹ and *g*². Also by reason of the sides *h*² and *e*³ being parallel with each other and the planes of the piles, it is not 30 possible to widen the neck parts *b* and *b*' of the tenons *h* without deforming at least one of the sheet piles adjacent the appropriate neck part *b* or *b*', particularly the sheet pile *d*. But it is found that under tensile strain there is a tendency for 35 the tenons *h* to bend at the parts *b* and *b*' thus weakening the joint and also causing the claws *g* to spread outwards.

By modifying the joint as shown in Figure 2, 40 i. e. by locating each peak or ridge so that it is on a line perpendicular to the appropriate base *e*² at the centre O, i. e. parallel with the plane of each web *c* and *d*, the tenon portion *h* is thicker and therefore stronger at its root *b* (or *b*') whilst maintaining the same thickness *a* and *a*' at its 45 outer ends as occurs at the like parts in the known joint shown in Figure 1, and without the necessity of increasing the total or effective width of the cross-section of the joint. Also the roots *g*' of the claws *g* can be kept to sturdy proportions and the overhang *l* from the straight parts 50 of the piles *c* and *d* can be kept shorter than the known form of joint shown in Figure 1. It will be seen by reference to Figure 2 that the proposed modification of the form of joint in question can 55 be stated as characterised in that the line

S-O-S¹ is perpendicular to the abutting bases e² or parallel with the planes of the sheet piles, and that this depends to some extent by the fact that in order to achieve the foregoing results the hook e is disposed practically wholly unilaterally of the plane of the web.

The strength of the joint may be brought to its maximum strength by reinforcing the tenon or root parts g¹ of the claws g up to a resistance equal to the resistance of the material at a.

From the foregoing it will be appreciated that the present invention can be summarised as being a sheet pile comprising a main web c or d with complementary hook-joint forming marginal parts at its ends located uni-laterally of one face of the web, said marginal parts each comprising a tenon h co-extensive with the web c or d and formed with a substantially triangular outer end hook e, and a claw g spaced inwardly of the hook e and having an inner side g² forming with the inner side h² of the adjacent tenon and the base side e² of the adjacent substantially triangular hook e a channel complementary with one of the said hooks, the two hooks having peaks e⁴ located in a common plane S-O-S¹ parallel with the plane of the web and intersecting approximately the centres of the base sides e² of the hooks, which base sides are normal to the plane of the web and diagonal with respect to the inner sides h² of the said tenons, so that the root ends b and b' of the tenons, i. e. those which join the normal web c or d are thicker than the outer ends a and a' which join the said hooks.

I claim:

A sheet pile comprising a main web with complementary hook-joint forming marginal parts at its ends located uni-laterally of one face of the web, said marginal parts each comprising a tenon co-extensive with the web and formed with a substantially triangular outer end hook, and a claw spaced inwardly of the hook and having an inner side forming with the inner side of the adjacent tenon and the base side of the adjacent substantially triangular hook a channel complementary with one of the said hooks, the two hooks having peaks located in a common plane parallel with the plane of the web and intersecting approximately the centres of the base sides of the hooks, which base sides are normal to the plane of the web and diagonal with respect to the inner sides of the said tenons, so that the root ends of the tenons, i. e. those which join a normal web, are thicker than the outer ends which join the said hooks.

AUGUST SCHAAACK.
